APPARATUS FOR THE CONTROL OF HIGHWAY CROSSING SIGNALS

Robert M. Laurenson, Elkhart, Ind., assignor to
The Union Switch and Signal Company, Swiss-
vale, Pa., a corporation of Pennsylvania

Application September 5, 1942, Serial No. 457,442

4 Claims. (Cl. 246—130)

My invention relates to apparatus for the control of highway crossing signals, and has particular reference to the organization of such apparatus into novel and improved highway crossing signal control systems of the class incorporating coded track circuits. More particularly, my invention relates to highway crossing signal control systems incorporating coded track circuits of the class disclosed in my copending application for Letters Patent of the United States, Serial No. 406,995, filed August 15, 1941, for Coded track circuit system of railway signaling.

In the said copending application, I disclosed improved forms of coded track circuits incorporating apparatus for governing approach controlled functions without use of line wires. This apparatus includes entrance end apparatus comprising a source of power connected to the rails in multiple with the track relay at the entrance end of a section, and exit end apparatus comprising another source of current and a detector relay connected alternately to the rails at the exit end of the section. The arrangement is such that when the exit end source is connected to the rails, the two sources oppose each other in the track relay winding, and when the exit end source is disconnected from the track rails, both the track relay and the detector relay are energized by current supplied from the entrance end source.

In the application of a system of the type described to the control of a highway crossing signal positioned at the crossing intermediate the two ends of a track section, means must be provided to terminate operation of the crossing signal after a train clears the crossing, without interfering with the control of the wayside signals governing traffic in the section. It is, therefore, an object of my present invention to provide means in a system of the type disclosed in my said copending United States application, Serial No. 406,995, for adapting such system to the control of highway crossing signals.

Another object of my invention is the provision of a novel and improved highway crossing signal system incorporating coded track circuits arranged to effect operation of a crossing signal without use of line wires.

An additional object is to provide a novel and improved highway crossing signal control system.

In practicing the invention, the above-mentioned and other important objects and characteristic features of my invention which will become readily apparent from the following de-

scription, are attained by incorporating an auxiliary relay into the track circuit arrangement shown in my copending United States application, Serial No. 406,995; by utilizing means responsive to traffic in the next adjacent track circuit in advance of the crossing for at times connecting the auxiliary relay to the rails of its associated circuit in lieu of the detector relay and exit end source of that circuit, and by controlling the crossing signal by both the auxiliary relay and the detector relay.

I shall describe one form of apparatus embodying my invention, and shall then point out the novel features thereof in claims.

The accompanying drawing is a diagrammatic view of one form of apparatus embodying my invention.

Referring to the drawing, the reference characters 1 and 1a designate the track rails of a stretch of railway track over which traffic normally moves in the direction indicated by an arrow or from left to right as viewed in the drawing. The rails 1 and 1a are divided by insulated joints 2 into a plurality of successive adjoining track sections of which only one section, E—F, is represented complete in the drawing. This section in turn is divided by joints 2 at a cut-section location Ea into subsections 2T and 3T. Subsection 2T is intersected at grade adjacent to its exit end Ea by a highway H, and located adjacent to such intersection is a highway crossing warning signal such as an electric bell XS. Signal XS is controlled by a relay XR and is provided with an operating circuit which extends from one terminal B of a suitable source of current, through back contact 9 of relay XR and the operating element of signal XS to terminal C of the same source of current.

The operation of railway traffic in section E—F is governed by a wayside signal S positioned at the entrance end E of the section. This signal and the highway crossing signal XS are controlled by coded track circuit apparatus provided for subsections 2T and 3T and arranged to cooperate in a novel manner. The specific form of the track circuit apparatus provided for subsection 3T is immaterial to the present invention and it may take any desired form which incorporates means for detecting operation of a track relay by coded energy received from the rails of the section. For the purposes of the present description it is deemed necessary to show only a typical form of coded track circuit comprising a battery 10 intermittently connected to the rails at the exit end F of the subsection over a contact 11 of

a constantly operating coder 3CT; and code detecting apparatus provided for subsection 3T at its entrance end E_a. This code detecting apparatus, as shown, comprises a track relay 3TR connected to the rails at the entrance end of subsection 3T, a code detecting relay HR, and a decoding transformer 3DT. Relay 3TR controls code detecting relay HR through the medium of transformer 3DT in the usual manner so that relay HR is held picked up when and only when relay 3TR responds to coded energy received from the rails of its subsection.

Referring now to subsection 2T, the apparatus at the entrance end E is arranged in accordance with the disclosure of my copending United States application, Serial No. 406,995. It comprises a track relay 2TR and a resistor 12, connected in series across the rails, with a track battery 14 and another resistor 15 also connected in series and the two latter elements being connected in multiple with the first two. Relay 2TR is of the polar biased type and bears an arrow pointing from left to right as viewed in the drawing to indicate that it is responsive to current of such polarity that its left-hand terminal is positive. Battery 14 connected therewith is poled to supply current of such given polarity to the relay. Relay 2TR has associated therewith decoding apparatus, indicated conventionally in the drawing and designated by the reference character DA, arranged to govern the associated wayside signal S in the usual manner. That is to say, the control is such that signal S will be caused to display its stop indication whenever relay 2TR is either steadily picked up or released, and will be caused to display a less restrictive aspect whenever relay 2TR responds to coded energy.

The exit end apparatus for subsection 2T comprises another battery 16, a detector relay DR, a slow-releasing repeater relay DPR, an auxiliary relay AR, and a constantly operating coding device or coder 2CT. This apparatus is also arranged in accordance with the disclosure of my copending United States application, Serial No. 406,995. When relay HR is picked up in response to the operation of its associated track relay 3TR by coded energy received from the rails of its associated subsection, either a battery 16 or the relay DR is connected across the rails of subsection 2T through front contact 22 of relay HR according as contact 20 of coder 2CT is in its front or back position, respectively, a resistor 21 being included in series with the battery 16. Battery 16 is poled in such a manner that when it is connected with the track rails, the two batteries 14 and 16 buck or oppose each other in the winding of track relay 2TR. Relay 2TR is therefore deenergized when battery 16 is connected in circuit with the track rails. When, however, battery 16 is disconnected from the rails, then track relay 2TR and detector relay DR become energized, in multiple, by current supplied from battery 14.

Detector relay DR controls its associated slow releasing repeater relay DPR through the medium of a decoding transformer 2DT in such a manner that relay DPR is energized momentarily each time relay DR is picked up or released. Relay DPR thus detects a coding operation of relay DR and is held steadily in its picked-up position by its slow releasing characteristic whenever relay DR is intermittently picked up and released.

In accordance with the present invention, re-

lay HR when released connects auxiliary relay AR to the rails of subsection 2T in lieu of battery 16 or relay DR. This is effected by an obvious path including the back point of contact 22 of relay HR and the winding of relay AR. It follows that when relay HR is released and subsection 2T is vacant, relay AR is energized by current supplied from battery 14.

Signal control relay XR is governed jointly by relays DR and AR, and is energized over an obvious circuit whenever front contact 24 of relay DPR or front contact 25 of relay AR is closed.

When section E—F is vacant, the apparatus is in its normal condition as represented in the drawing. In this condition, relay HR is energized in response to the operation of relay 3TR by coded current received from the rails of its subsection, and as a result the track circuit apparatus of subsection 2T functions to operate relays 2TR and DR at a rate corresponding to the rate of operation of coder 2CT. Relay DPR is therefore energized and it in turn energizes relay XR so that signal XS is deenergized.

When a train enters subsection 2T, the coded currents supplied from battery 16 and battery 14 are shunted away from relay 2TR, and that relay assumes its released position. Relay DR likewise assumes its released position since it is also shunted by the train. Repeater relay DPR accordingly releases and in turn releases relay XR to cause that relay to complete the energizing circuit of signal XS. This condition of the apparatus is maintained until the train enters section 3T.

When this happens, relay 3TR is shunted and assumes its released position, whereupon relay HR becomes deenergized and releases to open its front and close its back point of contact 22. This action disconnects battery 16 and relay DR from the rails of subsection 2T, and connects auxiliary relay AR to such rails. The auxiliary relay is of course shunted and remains released as long as any part of the train occupies subsection 2T. When the rear end of the train leaves subsection 2T and removes its shunt, relays 2TR and AR become steadily energized by current supplied from battery 14, and as a result both relays pick up. This steady energization of relay 2TR has no material effect upon the apparatus controlled thereby and hence does not affect signal S, but relay AR in picking up energizes relay XR and hence terminates operation of signal XS.

After the train vacates subsection 3T, relay 3TR responds to the coded current available in the rails and causes relay HR to pick up. This action disconnects relay AR from and connects battery 16 and relay DR to the rails of subsection 2T. Relay AR accordingly releases, but with the track circuit apparatus of subsection 2T restored to its normal condition, relays 2TR and DR intermittently pick up and release and relay DPR accordingly picks up. The crossing signal control relay XR, as indicated, is preferably provided with a slow releasing characteristic selected to maintain it picked up during the interval that elapses between the release of relay AR and the picking up of relay DPR, so that the crossing signal will not be operated momentarily when the train vacates subsection 3T.

From the foregoing description, it is readily apparent that I have provided a novel and improved coded track circuit system for controlling a highway crossing signal positioned at a cut-section location in a track section. This system is characterized by the fact that no line wires are

required to terminate operation of the signal without effecting operation of the wayside signal governing railway traffic in the section.

Although I have herein shown and described only one form of apparatus for the control of highway crossing signals embodying my invention, it is understood that various changes and modifications may be made therein within the scope of the appended claims without departing from the spirit and scope of my invention.

Having thus described my invention, what I claim is:

1. In combination with a stretch of railway track including a track section having a portion provided with a track circuit comprising a source of current connected across the rails at one end of the section and a relay connected intermittently to the rails at an intermediate point in the section over a circuit including a constantly operating contact of a coder device, another relay, means governed by traffic on another portion of said section for at times disconnecting the said circuit connection of said first relay from said track rails and constantly connecting said other relay to said track rails, and means governed jointly by said first and said other relay.

2. In combination with a section of railway track having a portion provided with a track circuit of the class comprising a first source of current and a first relay connected in multiple to the rails at one end of the section and a second source and a second relay connected alternately to the rails at an intermediate point in the section according as a constantly operating coding device operates its contacts to one position or the other, said first and second sources being poled in such manner as to oppose each other in the winding of said first relay, a third relay, means governed by traffic conditions on an advance portion of said section for at times disconnecting said second source and second relay from said track

rails and connecting said third relay in circuit with said rails, and a signaling device governed by said second and third relays.

3. In a railway signal system of the class wherein a signal at the entrance end of a track section for governing traffic in said section is controlled by a track circuit comprising a first relay and a first source of current connected in multiple to the rails at said entrance end and a second relay and a second source of current connected alternately to the rails at an intermediate point in said section over a circuit path including a constantly operating contact of a coding device, said second source being poled to oppose said first source in the winding of said first relay, the combination of an auxiliary relay, a track circuit for an advance portion of said section, means governed by said advance track circuit for at times constantly connecting said auxiliary relay to the rails of said section in lieu of said second source and second relay, and signaling means governed by said auxiliary relay and by said second relay.

4. In combination, a section of railway track intersected intermediate its ends at grade by a highway, a highway crossing signal at such intersection, a track circuit provided for a given portion of said section comprising a track relay and a first source of current connected in multiple to the rails at one end of said section and a second relay and a second source connected alternately to the rails adjacent to said intersection, a signal governing railway traffic in said section and controlled by said track relay, a track circuit for a remaining portion of said section, an auxiliary relay, means governed by said remaining portion track circuit for at times constantly connecting said auxiliary relay to the rails of said given section portion in lieu of said second source and second relay, and means governed jointly by said second relay and said auxiliary relay.

ROBERT M. LAURENSON.
